[57] **CLAIM**

The ornamental design for a decorative molding for retainer flange, as shown and described.

DESCRIPTION

FIG. 1 is a perspective view of a decorative molding for retainer flange according to my new design.

FIG. 2 is a front view of the decorative molding for retainer flange of FIG. 1.

FIG. 3 is a top view of the decorative molding for retainer flange of FIG. 1.

FIG. 4 is a right side view of the decorative molding for retainer flange of FIG. 1, the left side view being a mirror image of the right side view.

FIG. 5 is a bottom view of the decorative molding for retainer flange of FIG. 1.

FIG. 6 is a rear view of the decorative molding for retainer flange of FIG. 1.
